UNITED STATES PATENT OFFICE.

ARTHUR L. HAWKESWORTH, OF BUTTE, MONTANA, ASSIGNOR TO HAWKESWORTH DRILL COMPANY, OF BUTTE, MONTANA, A CORPORATION OF DELAWARE.

DRILL.

Application filed July 7, 1922. Serial No. 573,988.

To all whom it may concern:

Be it known that I, ARTHUR L. HAWKESWORTH, a citizen of the United States, residing at Butte, in the county of Silverbow and State of Montana, have invented certain new and useful Improvements in Drills, of which the following is a specification.

My invention has relation to improvements in drills having detachable bits which may be quickly and readily detached when occasion arises therefor, for example, where a bit must be removed for sharpening and a new bit substituted, or when it is desired to take the bit off for safe-keeping, or for any other purpose. A further object of the invention is to provide a passage-way in the shank for the flow of water or air, said passage-way communicating with a duct between the shank and bit for the lateral discharge of the water or air into the hole. A further object is to provide a drill having communicating ports in bit and shank for the flow of cleaning fluid therethrough, with auxiliary outlet ports in the shank. A further object is to provide a drill having a detachable bit terminating in a plurality of cutting edges, some of which are notched to relieve the bit of cutting surface where not required. Further objects will be better apparent from a detailed description of the invention in connection with the accompanying drawings, in which—

Figure 1 represents an elevation of my improved drill turned so as to present the narrow ends of the central or main interlocking groove and tongue of the shank and bit respectively; Fig. 2 is a side elevation of the drill; Fig. 3 is an elevation of the bit detached from the shank and turned to present the narrow end of its central tongue; Fig. 4 is an elevation of the shank turned to present the narrow end of its central groove receiving the corresponding tongue of the bit, and the wide ends of the tongues bounding said groove which enter corresponding grooves of the bit; Fig. 5 is an elevation of the drill turned at an angle of 45° from Fig. 1 so as to present the sides of the notched cutting legs; Fig. 6 is an elevation of the bit detached from the shank and turned at an angle of 90° from Fig. 5 so as to present the sides of the cutting legs that are not notched but extend from side to side of the bit; Fig. 7 is a plan of the cutting surface of the bit; Fig. 8 is a plan

of a bit cutting surface showing three of the cutting legs notched instead of two; Fig. 9 is an elevation of a form of drill showing a groove for the passage of water or air in the bit tongue instead of in the shank as shown in Fig. 1; Figures 10 and 11 are views of the drill shown in Fig. 9 with the bit and shank detached similar to Figures 3 and 4 of the main form; Fig. 12 is a modified form of drill similar in all respects to the main form (Fig. 2) except that the inclined ports for lateral discharge of water discharge below the ends of shank groove instead of at each side beyond said groove; Fig. 13 is a further modification showing central tongue and groove with vertical sides instead of dovetailed.

Referring to the drawings, and for the present to Figures 1 to 7 inclusive, 1 represents a drill-bar or shank and 2 the bit adapted to be passed across the axis thereof, said shank and bit having cooperative formations whereby they are effectively interlocked against relative displacement, the bit, at the same time, being readily detachable from the shank. These interlocking formations are the same as those shown in my Letters Patent No. 1,328,325, dated January 20, 1920, and consist in a dovetail groove 3 in the shank bounded by dovetail tongues 4, 4 which cooperate with a dovetail tongue 5 on the bit bounded by dovetail grooves 6, 6, all of said formations being inclined to the axis of the drill. The side walls of the tongues 4, 4 taper in the general direction toward the cutting end of the drill while the side walls of groove 3 taper in the opposite direction so that on inserting the narrow end of tongue 5 into the wide end of groove 3, the narrow ends of tongues 4, 4 of the shank will at the same time be received by the wide ends of grooves 6, 6 of the bit, and as the bit is moved across the shank, the respective formations will interlock until further movement of the bit is arrested, when the axis of shank and bit are in alinement. This arrest is effected by the wedging action between tongue 5 and groove 3 on the one hand, and the tongues 4, 4 and grooves 6, 6, on the other hand, the reverse tapers of the respective tongues and their cooperating grooves operating to effect a positive locking of the bit to the shank. Obviously, the blows to which the drill is subjected in drilling operations will tend

to tighten the bit on the shank, said bit being readily removed, however, by a slight blow with a hammer against the bit on the same side with the narrow end of tongue 5. 5 In the present case the bit is provided with oppositely disposed cutting legs 7, 7 and 7', 7', the legs 7, 7 terminating in beveled faces *a*, *a* extending continuously from one leg to the other to form a cutting edge *e*, while the legs 7', 7' have inwardly inclined faces *c*, *c* cut in them, said faces intersecting bevel faces *b*, *b*, *b*, *b*, of said legs 7', 7' and removing the inner part of each cutting edge *e'*, *e*. Thus the cutting 10 legs 7', 7' have cutting edges only on the outer part toward their peripheral edges, while legs 7, 7 have cutting edges extending substantially from the center of bit to the periphery thereof. The object of thus decreasing the cutting edge at the center of the bit is twofold. In the first place, less material has to be removed from the center of a drilled hole than from the greater outer area, and in the second place, to produce the 15 inclined faces *c*, *c* the cutting surface of the bit is provided with the notches *n*, *n* which relieve the resistance on the bit, facilitate the washing out of the cuttings, and result in faster cutting by the bit. 20 The shank 1 is provided with an axially disposed port or passage-way *d* having an outlet communicating with a groove *g* connected to groove 3 and forming the bottom thereof, and the bit 2 is provided with a port 25 *d'* in alignment with port *d*. The shank 1 is further provided with two inclined ports *h*, *h* branching off from port *d* and each having an outlet just under the bit 2 between adjacent cutting legs. In the drilling operation 30 water (or air) is caused to flow through port *d*, some of said water discharging through groove *g*, some through port *d'* and some through ports *h*, *h*, and washing the cuttings away from the cutting 35 surface of the bit. If the port *d'* only were provided for the discharge of the water (as has heretofore been the case) the drill would have to be withdrawn in case this port became stopped up. In the present case not 40 only will the drill operate satisfactorily when port *d'* is stopped up, but this port may even be dispensed with entirely. 45

In Fig. 8 I show a plan of the cutting face of another form of bit wherein three of 50 the legs 7', 7', 7' are provided with notches *n* leaving but one leg 7 having a cutting edge *e* extending from the center to the peripheral edge.

Figures 9, 10 and 11 show another form of the drill differing from the main form in 60 that instead of groove *g* being provided in the shank, a groove *g'* is formed in the bottom face of tongue 5' of the bit and the axial port *d'* is omitted from the bit as well as inclined ports *h*, *h*. 65

The modification shown in Fig. 12 is similar to the main form with the exception that inclined ports *h'*, *h'* are disposed at an angle of 90° from their position in Fig. 2, discharging beneath the ends of tongue 5. 70

In Fig. 13 the interlocking formations of shank and bit are modified somewhat, the tongue 10 of bit 2' and its cooperating groove 11 having perpendicular sides instead of being dovetailed, and tongues 12, 12 of the 75 shank 1' and its cooperating grooves 13, 13 in the bit also having perpendicular sides, the groove and cooperating tongue gradually widening toward the cutting end of the bit as in the main form. 80

Obviously, it is within the spirit of my invention to construct the cooperative formations of bit and shank of the main form in the manner just described, or combine the various modifications illustrated in any 85 manner most desirable to suit given conditions, since all of the novel features described are capable of being combined in one form of drill.

Having described by invention, I claim: 90

1. In combination with a drill-bar or shank, a bit detachably secured thereto, said shank having an axially disposed passage-way extending therethrough, and one of the bit-engaging transverse surfaces of the 95 shank having a groove extending from side to side thereof.

2. In combination with a drill-bar or shank, a bit movable across the axis of the shank, a transverse dovetail tongue tapering 100 in a given direction and bounding grooves tapering in the opposite direction formed on one of the members, a corresponding dovetail tapering groove and bounding tongues on the opposite member interlocking with 105 the formations on the first member, the transverse engaging surfaces between the members being inclined to the axis of the shank, said shank being provided with an axial port extending therethrough, said port 110 communicating with a longitudinally disposed groove formed in the tongue of the bit. 115

In testimony whereof I hereunto affix my signature.

ARTHUR L. HAWKESWORTH.
